[57] CLAIM

The ornamental design for a gas cooktop grate, as shown and described.

DESCRIPTION

FIG. 1 shows a gas range having a gas cooktop grate according to the invention installed thereon;

FIG. 2 shows a top plan view of the assembled grate; FIG. 3 shows an isometric view of a corner component of the grate, all four corner components being identical;

FIG. 4 shows a front view of the corner component, the rear view being identical;

FIG. 5 shows a top view of the corner component;

FIG. 6 shows a side view of the corner component, the opposite side view being identical;

FIG. 7 shows a bottom view of the corner component;

FIG. 8 shows an isometric view of a center component of the grate, the two center components being identical;

FIG. 9 shows a front view of the center component;

FIG. 10 shows a top view of the center component;

FIG. 11 shows a right side view of the center component of FIG. 10;

FIG. 12 shows a left side view of the center component of FIG. 10;

FIG. 13 shows a bottom view of the center component; and,

FIG. 14 shows a rear view of the center component.
